[57] CLAIM

The ornamental design for a table, as shown and described.

DESCRIPTION

FIG. 1 is a top plan view of a table showing my new design;

FIG. 2 is a side elevational view thereof, all sides being identical;

FIG. 3 is an elevational view looking in the direction of arrows 3—3 of FIG. 1;

FIG. 4 is a bottom plan view relative to FIG. 3;

FIG. 5 is a top plan view of an alternative embodiment of a table showing my new design;

FIG. 6 is a side elevational view relative to FIG. 5, all sides being identical;

FIG. 7 is a bottom plan view relative to FIG. 5; and

FIG. 8 is a side elevational view rotated 45 degrees relative to FIG. 5.
